TRUNDLE SAND TOY

Sidney A. Tarrson, 777 S. Tripp,
Chicago, Ill. 60624

Filed Oct. 30, 1967, Ser. No. 9,204

Term of patent 14 years

(Cl. D34—15)

FIG. 1 is a perspective view of a trundle sand toy viewed from one side thereof, showing my new design, the opposite side being substantially the same;

FIG. 2 is a front elevational view thereof;

FIG. 3 is a rear elevational view thereof;

FIG. 4 is a top plan view thereof;

FIG. 5 is a bottom plan view thereof to reduced scale.

I claim:

The ornamental design for a trundle sand toy, as shown and described.
